A. M. Putnam,

Double-Acting Pump,

No 35,258

Patented May 13, 1862.

UNITED STATES PATENT OFFICE.

ALBERT M. PUTNAM, OF ANTRIM, NEW HAMPSHIRE.

IMPROVEMENT IN PUMPS.

Specification forming part of Letters Patent No. 35,258, dated May 13, 1862.

To all whom it may concern:

Be it known that I, ALBERT M. PUTNAM, of Antrim, in the county of Hillsborough and State of New Hampshire, have invented an Improved Double-Acting Force-Pump, of which the following is a full, clear, and exact description, reference being had to the accompanying drawings, making part of this specification, in which—

Figure 1 is a view of the pump; Fig. 2, a vertical section through the same; Fig. 3, a view of the under side of the cylinder; Fig. 4, a plan of the base with the cylinder removed.

The object of my present invention is to produce a double-acting force-pump which will be cheap and durable in its construction and all the valves of which will be readily accessible if they should require repairs; and my invention consists in the pump which I will now proceed to describe in such terms that others skilled in the art may understand and use my invention.

In the said drawings the body of the pump A is a cylinder with flanges a at top and bottom. A cap, B, is secured on the top of the cylinder by screw-bolts passing through the flange, and the cylinder rests on and is secured to a base, C, of sufficient depth to contain water-ways, which are cast in it. As all the valves which are used—four in number—are placed on the upper surface of this base C, they are all readily accessible by removing the base from the cylinder. To the cap B is attached a standard, b, to which is pivoted the brake D, by which the piston E is operated.

The outlet pipe or nozzle F is also attached to this cap. Within the cylinder A is another cylinder, G, in which the piston E moves. It is attached to the cylinder A by division-plates or partitions c d e f, which thus form chambers H I J K. The larger one, H, I term the "air-chamber." The top of the cylinder G is cut down opposite to each of the chambers I and J, thus forming ports g h, and the partition f is cut off at its lower end to form a communication from the chamber H to the chamber K. This chamber K communicates at top by a hole through the cap with the nozzle F. The two cylinders with the partitions may all be cast in one piece. The base C con-

tains a water-way, i, into which opens the induction-pipe k, and which has two ports commanded by flap-valves l m. Another water-way, n, (shown dotted in Fig. 4,) has an open port, o, and one commanded by a valve, p, and the third water-way, q, has an open port, r, and one commanded by a valve, s. All these flap-valves open upward from the upper side of the base. When the cylinder A is in position on the base, the several ports in the base occupy the following positions relative to the chambers: The open port r and the one covered by the valve l open into the central cylinder, G, the port s into the chamber H, the port p into the chamber K, the port o into the chamber J, and the port m into the chamber I.

The pump being full of water, the following is its operation: As the piston E is raised, as in Fig. 2, the valve l is lifted, and water is drawn into the lower part of the cylinder G from the induction-pipe k. The valves s and m being shut down, the water above the piston is forced through the port h, down the chamber J, through open port o and water-way n, lifting the valve p into the chamber K and out of the nozzle F. When the piston E descends at the next stroke, the valves l and p are closed, the valve m is opened, and water is drawn from the pipe k through this valve up the chamber I and through port g at the top of this chamber into the cylinder G above the piston, while the water which was below the piston is forced through the open port r, water-way q, and, lifting the valve s, passes into the chamber H, thence under the lower end of the partition f, which, as before stated, is cut off shorter than the others, and up the passage K to the nozzle F.

The outlet or nozzle F is formed with an orifice at its outer end at u and another one at v at the top of the straight part of the pipe, it being intended to apply a screw-cap (which is made to fit either opening) to the outer end, u, when a hose is attached at v, and when the hose is not to be used the cap may be screwed on at v. A tube, x, passes through the side of the base C. It has a small hole on each side of it and corresponding holes opening into the water-ways n i. When the tube is turned so that its holes are opposite those on the walls of the water-ways, air is admitted

to the inside of the pump, and it empties itself of water through the induction-pipe *k*. This is sometimes necessary to prevent the pump from freezing up in cold weather. At other times the tube *x* is turned so as to close the openings into the water-ways.

What I claim as my invention, and desire to secure by Letters Patent, is—

The above-described pump, consisting of

the piston *E*, cylinders *A* and *G*, chambers *H* *I* *J* *K*, with ports *g* and *h*, in combination with the base *C*, containing water-ways *i* *n* *q*, with open ports *r* *o* and valves *l* *m* *s* *p*, arranged and operating substantially as described.

ALBERT M. PUTNAM.
